(57) **CLAIM**

The ornamental design for a tree stand platform, as shown and described.

DESCRIPTION

FIG. 1 is a top, front perspective view of a tree stand platform showing my new design;

FIG. 2 is a top plan view thereof;

FIG. 3 is a front elevational view thereof;

FIG. 4 is a right side elevational view thereof, the left side elevational view being identical; and,

FIG. 5 is a rear elevational view thereof.

The broken lines are for illustrative purposes only and form no part of the claimed design.
